UNITED STATES PATENT OFFICE.

JAMES D. FRARY, OF NEW BRITAIN, CONNECTICUT, ASSIGNOR TO LANDERS,
FRARY & CLARK, OF SAME PLACE.

DESIGN FOR CUTLERY-HANDLES.

Specification forming part of Design No. 7,862, dated November 17, 1874; application filed November 6, 1874.
[Term of Patent 7 years.]

CASE D.

To all whom it may concern:

Be it known that I, JAMES D. FRARY, of New Britain, in the county of Hartford and State of Connecticut, have invented a new Design for Cutlery-Handle; and I do hereby declare the following, when taken in connection with the accompanying drawings and the letters of reference marked thereon, to be a full, clear, and exact description of the same, and which said drawings constitute part of this specification, and represent a side view of a knife.

This invention relates to a design for the handle for table-cutlery, here represented as for a knife; but it will be understood that the design applies to forks and other articles of table-service, the design having special reference to the "bolster" and "tip."

The design consists in the peculiar ornamentation of the bolster and tip together or separately, and as shown in the accompanying illustration.

A is the bolster, the surface of which is or-

namented with a "spear-head" shaped figure running from the bolster to the body of the handle, as shown in the illustration. B is the tip, its surface ornamented with a figure corresponding to that of the bolster, and in like manner running into the body of the handle, as shown.

The bolster and tip may be used together in the same handle, or separately, each with different tip or bolster, as the case may be. I therefore do not confine my design to the combination of the tip and bolster in the same handle; but

I claim—

The design for cutlery-handle, consisting of the spear-head shaped ornament on the bolster and tip, together or separately, as shown and described.

JAS. D. FRARY.
